UNITED STATES PATENT OFFICE

JOHN H. WILHELM, OF LONG ISLAND, NEW YORK, ASSIGNOR, BY MESNE ASSIGNMENTS,
TO MARGON CORPORATION, OF NEW YORK, N. Y., A CORPORATION OF NEW YORK

DOLL

Application filed March 14, 1929. Serial No. 346,832.

This invention relates to a doll, and an object is to provide a doll of the so-called moulded type having a sound producing device appropriately secured in position therein in somewhat the general relation as shown and described in my copending application Serial No. 346,831.

A more detailed object is to provide simple, efficient and practical means by which a sound producing device may be operatively mounted within a hollow moulded doll body or head.

A further detailed object is to provide a doll having relatively movable head and limb parts and to provide elastic stringing means for said parts serviceable also as supporting means for the sound producing device.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a transverse sectional view through a doll constructed in accordance with this invention.

Fig. 2 is a rear elevational view of the structure seen in Fig. 1, a portion being broken away and shown in vertical section approximately upon the plane of line II—II of Fig. 1.

Fig. 3 is a fragmentary detail sectional view similar to a left hand portion of Fig. 1 but illustrating a modified construction of said portion.

Referring to the drawings for describing in detail the structures therein illustrated, it may be first mentioned that sound producing

devices for inclusion in dolls and like toys, although made up in various shapes and sizes, usually consist of a small cylindrical casing, as for instance a short section of cardboard "mailing-tube", closed at its opposite ends by suitable metallic cap pieces at least one of which is perforated so that sound produced by mechanism within the casing may emanate to the outer atmosphere. A sound producing device of this type is accordingly illustrated herein, but it will be understood that the invention is not necessarily restricted to the use of this type of sound producing device.

According to the present invention it is proposed that a moulded doll body may be provided, preferably through its back wall, with a large opening as L of such shape and size as to loosely accommodate the sound producing device therethrough.

The sound producing device illustrated is indicated generally by the reference character G, consisting of the cylindrical portion 1 and the opposite end cap pieces 2 and 3.

Arranged within the hollow of the body 70 adjacent the opening L is a platform member H having its main surface as 4 facing toward said opening. This platform member may be of any form or construction but is preferably shaped up from a suitable piece 75 of sheet metal providing prongs as 5 by which it is conveniently rigidly attached to the interior portion of the front wall 6 of the doll body. A marginal ledge 7 is provided about the surface 4 so as to constitute with 80 said surface an appropriate shallow seat for receiving and loosely fitting about the inner end of the sound producing device G which is conveniently placed into the interior of the body and against said seat through the opening L as clearly seen in the drawings.

The outer end surface as 8 of the sound producing device is approximately flush with the outer surface of the rear wall of the body.

A sheet as 9 of suitable material, such as muslin or cheese cloth, may be placed over the outer surface of the sound producing device and pasted onto the adjacent outer surface of the rear wall of the doll body for retaining the sound producing device against outward displacement. It will be understood however that any other appropriate means may be employed for retaining the sound producing device against displacement, as may be found most expedient, the sheet of cloth being nevertheless highly desirable for this purpose in view of its porosity whereby the sounds produced by the sounding device may readily flow outwardly from the body, the cloth meanwhile preventing movement of dust and dirt into the body.

In instances where the doll includes relatively movable members, such as the head 10 and limbs 11 shown, the stringing employed for holding the head and limbs movably connected with the body may consist of an endless elastic cord as 12. A metallic hook as 13 carried by this cord may engage a suitable anchor fixed within the head, and other hooks as 14—14 also carried by the cord may engage the limbs. The two strands as 15 and 16 comprising the mid portion of this cord may be spread apart to receive the sound producing device between them, as indicated, so that said strands, being in engagement with relatively opposite side wall portions of the sound producing device, and exerting substantially equal force against said opposite sides, will assist in retaining the sound producing device against movement with respect to the seat in the platform H.

In the modification Fig. 3 the structure is the same in all respects as above described, but it is proposed by this figure that if desired the seat for the inner end of the sound producing device may be built up as an integral moulded feature of the material of the doll body. In this figure the front wall 6 of the doll body is formed with a plurality of integrally moulded extensions 17 interiorly of the body each having a notch 18 at its inner end and said notches collectively providing the required seat for the sound producing device.

It is noted that in each of the structures illustrated objectionable movement of the sound producing device is prevented not only by engagement of said device with the platform, the elastic cord, and the cloth sheet 9, but also by the walls of the opening L so that, while said sound producing device is permitted slight movement in various directions, suitable to prevent injury to the delicate mechanism within said device, for instance when the doll is dropped, it will yet be securely retained against permanent displacement at all times. The yielding pressure of the elastic cord will always hold it yieldingly in a proper normal position.

As many changes could be made in this construction without departing from the scope of the invention, as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A doll comprising a hollow moulded body having front and back walls spaced apart, a separately formed metallic platform member arranged interiorly of the body, said platform member resting against the inner surface of the front wall and having prongs embedded into said front wall, the back wall having an opening therethrough adjacent said platform member, said platform member having a seat facing toward said opening, a sound producing device extending through said opening and engaging within said seat, and means to retain the sound producing device against displacement from said seat.

2. A doll comprising a hollow moulded body having front and back walls spaced apart, a sound producing device within said body, said walls each having a part engaging the sound producing device serving collectively to support said device in position while allowing it a slight degree of movement with respect to the body, and means to cushion the movements of said device, said cushioning means engaging the sound producing device at a location spaced intermediate those parts of the front and back walls which engage the sound producing device.

3. A doll comprising a hollow moulded body having front and back walls spaced apart, separately formed head and limb members, a sound producing device within said body, said walls each having a part engaging the sound producing device serving collectively to support said device in position while allowing it a slight degree of movement with respect to the body, and elastic stringing connecting the head and limb members with the body having parts engaging the sound producing device to cushion the movements of said device.

4. A doll comprising a hollow moulded body having an opening through one wall thereof and having a platform provided upon the inner surface of an opposite wall aligned with said opening, a sound producing device, said opening being of a size to permit easy insertion of the sound producing device therethrough into position with the inner end portion of the sound producing device engaging said platform and with the outer end portion of the sound producing device positioned in said opening in close proximity to the walls thereof, the platform being formed with means having co-operative engagement with

the inner end portion of the sound producing device to hold said inner end against undesirable lateral movement with respect to the body, and means engaging the outer end of
5 the sound producing device and fixed to the adjacent outer surface of the body adjacent said opening serving to hold the sound producing device in position upon said platform.

10 In testimony whereof I affix my signature.
JOHN H. WILHELM.
